his Attorney.

UNITED STATES PATENT OFFICE.

HERBERT A. WALLACE, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed December 21, 1923. Serial No. 681,947.

To all whom it may concern:

Be it known that I, HERBERT A. WALLACE, a citizen of the United States, residing at Edgewood Borough, in the county of Allegheny and State of Pennsylvania, have invented certain new and useful Improvements in Railway-Traffic-Controlling Apparatus, of which the following is a specification.

10 My invention relates to railway traffic controlling apparatus of the type comprising train-carried governing means controlled by energy in the trackway. More particularly my invention relates to the 15 trackway portion of such apparatus.

I will describe three forms of apparatus embodying my invention and will then point out the novel features thereof in claims.

In the accompanying drawing Fig. 1 is 20 a view showing one form of trackway apparatus embodying my invention. Figs. 2 and 3 are views showing two modifications of the apparatus shown in Fig. 1 and also embodying my invention.

25 Similar reference characters refer to similar parts in each of the three views.

Referring first to Fig. 1, the reference characters 1 and 1^a designate the track rails of a stretch of railway track over which 30 traffic normally moves in the direction indicated by the arrow. The track rails of this stretch are divided by means of insulated joints 18, into a plurality of track sections, only one of which, section A—B, 35 is shown in the drawing. Section A—B is provided with a switch C of the usual and well known form for permitting traffic to move from section A—B into a siding Z. Associated with switch C is a switch circuit

40 controller D of any convenient form and comprising three contacts 2, 3 and 4. When switch C is normal, that is, when the switch is set for traffic movements along section A—B, contacts 2 and 3 are open and contact 4 is closed. When switch C is in any 45 other position, such as the reverse position to allow traffic to pass from section A—B into siding Z, contacts 2 and 3 are closed and contact 4 is open.

50 Means are also provided for supplying the section with train governing current. As here shown this means comprises a circuit which I shall term a "local circuit" over

which "local current" is supplied to the rails of the section in parallel.

It should be pointed out that the trackway apparatus herein shown and described is suitable for co-operation with train-carried governing means in such manner that when the train occupies a stretch of track 55 which is being supplied with train governing current the governing means causes a less restrictive indication such as "proceed" to be received on the train, and when the train occupies a stretch of track 60 to which the supply of train governing current is interrupted, a more restrictive indication such as "stop" is received on the train.

An impedance 5 is connected across the 70 rails adjacent the entrance end of the section, and a similar impedance 6 is connected across the rails adjacent the exit end of the section. The local current is supplied by a transformer T the primary 8 of which is 75 constantly supplied with alternating current from some source not shown in the drawing.

When switch C is normal, as shown in the drawing, the local circuit for section A—B 80 passes from secondary 7 of transformer T, through wire 9, contact 4 of circuit controller D, wire 10, impedance 5, through the rails of section A—B to impedance 6, wire 11, contact 13 and wire 14 back to secondary 85 7 of transformer T. Contact 13 may be controlled in any suitable manner such as by traffic conditions in advance. When this circuit is closed local current is supplied to the rails of the section throughout its length 90 and a train will receive a proceed indication throughout the section.

When switch C is reversed, however, the local circuit passes from secondary 7 of transformer T, through wire 9, impedance 95 12, contact 3 of circuit controller D, wires 15 and 16 to rail 1 and wires 15 and 17, and contact 2 of circuit controller D and wire 38 to rail 1^a, thence through the rails to impedance 6, wire 11, contact 13, wire 14, and 100 back to secondary 7 of transformer T. The impedance 12 is so designed as to be substantially equal to the two halves of impedance 5 in parallel, and so the local current flowing through the rails of the forward portion of section A—B will be sub- 105

stantially the same whichever circuit is closed. When the last traced circuit is closed local current is supplied to the forward portion of section A—B, that is, between the switch C and point B, but no local current is supplied to the rails of the rear portion of the section that is, the portion between switch C and point A. Under these conditions a train in the rear portion of the section will receive a stop indication, protecting the train against the open switch C, but a train in the forward portion of track receives a proceed indication. It is therefore plain that if a train is moving through the section and the switch C is reversed, the train will receive a stop indication if it is approaching the switch, but will continue to receive a proceed indication if it is receding from the switch. It will be clear that one purpose of contact 2 of circuit controller D is to insure that equal amounts of local current flow through each of the rails. Although a contact similar to contact 2 is used in practically all signaling systems for a different purpose, namely to insure the shunting of the track relay when the switch is reversed, this contact is not an essential part of my invention since the wheels and axles of a train occupying the stretch would accomplish the same result.

If it is desired to operate trains over section A—B in both directions the apparatus may be arranged as shown in Fig. 2. Two relays R and R', located adjacent the right hand and left hand ends, respectively, of section A—B, are normally de-energized and are controlled, by means not shown in the drawing, so that when a train moves through section A—B from left to right these relays are not affected, but when a train moves through this section from right to left relays R and R' are energized as the train enters section A—B and remain in their energized condition as long as any part of the train occupies this section. Relay R is what is known as the stick relay in single track absolute permissive signaling and relay R' is a repeater of relay R.

In addition to transformer T, the section A—B is further provided with a second local transformer T' similar to transformer T and a second contact 39 similar in function to contact 13. A fourth contact 19 is also added to circuit controller D and is arranged to be open when switch C is normal, but to be closed when the switch is reversed. When switch C is normal and section A—B is unoccupied or is occupied by a train moving from left to right the local circuit passes from the secondary winding 7 of transformer T, through wire 26, back contact 25 of relay R, wire 9, contact 4 of circuit controller D, wire 24, back contact 23 of relay R', wires 22 and 10, impedance 5, rails of section A—B, impedance 6, wire 11, contact

13, and wire 14, back to transformer T. Under these conditions a train proceeding from left to right through section A—B will receive a proceed indication throughout the section.

If, while relays R and R' are still de-energized, switch C is reversed, the local circuit will then pass from secondary 7 of transformer T, through wire 26, back contact 25 of relay R, wire 9, impedance 12, contact 3 of circuit controller D, wires 15 and 16 to rail 1 and through wire 15, contact 2 and wire 38 to rail 1^a, through the rails of the section to impedance 6, wire 11, contact 13, and wire 14, back to transformer T. When this circuit is closed a train between point A and switch C will receive a stop indication and a train between switch C and point B will receive a proceed indication.

When a train moving from right to left enters section A—B, the energization of relays R and R' completes a circuit, provided switch C is normal, which circuit passes from secondary 7 of transformer T', through wire 29, contact 39, wire 10, impedance 5, through the rails of the section to impedance 6, wires 11 and 28, front contact 25 of relay R, wire 9, contact 4, wire 24, front contact 23 of relay R', and wire 27 back to transformer T'. The train will thus receive a proceed indication throughout the section. If the switch C is reversed however, the local circuit will pass from secondary 7 of transformer T', through wire 29, contact 39, wire 10, impedance 5, through the rails of the section to switch C, from rail 1 through wire 16 and contact 2 to wire 38 and from rail 1^a to wire 38, contact 19, wire 30, impedance 31, wire 24, front contact 23 of relay R', and wire 27 back to secondary 7 of transformer T'. When this circuit is closed a train between switch C and point A will receive a proceed indication but a train between switch C and point B will receive a stop indication.

Referring now to Fig. 3, section A—B is provided, as in Fig. 2, with two relays R and R', controlled in the manner already explained. Circuit controller D in addition to contacts 2, 19, 3 and 4, is also provided with a fifth contact 32 arranged to be closed when switch C is normal, and to be opened when this switch is reversed.

When relays R and R' are de-energized, that is, when section A—B is unoccupied or is occupied by a train moving from left to right, one local circuit passes from secondary 7 of local transformer T, through wire 26, back contact 21 of relay R, wire 35, contact 4, wire 34, back contact 33 of relay R', wires 22 and 10, impedance 5, through the rails of the section to impedance 6, and wire 11, contact 13 and wire 14 back to secondary 7 of transformer T. When this circuit is closed

local current is supplied to section A—B throughout the length of the section. When relays R and R' are de-energized and switch C is reversed, local current flows from secondary 7 of transformer T, through wire 26, back contact 21 of relay R, wire 35, impedance 12, contact 3, wire 15, through wire 16 to rail 1, through contact 2 and wire 38 to rail 1^a, through the rails to impedance 6, wire 11, contact 13, and wire 18 back to secondary 7 of transformer T. Under these conditions section A—B is provided with local current between switch C and point B but with no local current between point A and switch C. A train proceeding from left to right through the section will receive a proceed indication throughout the section if switch C is normal but if switch C is reversed it will receive a stop indication between point A and switch C, and a proceed indication between switch C and point B.

When section A—B is occupied by a train moving from right to left relays R and R' are energized, and, if switch C is normal local current flows from secondary 7 of transformer T', through wire 29, contact 39, wire 10, impedance 5, through the rails of the section to impedance 6, wires 11 and 28, contact 25 of relay R, wire 36, contact 32 of circuit controller D, wire 37, front contact 23 of relay R', and wire 27 back to secondary 7 of transformer T'. When this circuit is closed local current is supplied to section A—B throughout its length and the train receives a proceed indication throughout the section. When relays R and R' are energized, and switch C is reversed local current flows from secondary 7 of transformer T', through wire 29, contact 39, wire 10, impedance 5, through the rails of the section to switch G, thence from rail 1, through wire 16, contact 2, wire 38, contact 19 to wire 30, and from rail 1^a, through wire 38 and contact 19 to wire 30, through impedance 31, wire 37, front contact 23 of relay R', and wire 27 back to secondary 7 of transformer T'. When this circuit is closed a train receives a proceed indication between switch C and point A and a stop indication between switch C and point B.

It should be pointed out that although in these drawings I have illustrated the local circuits controlled by the switch through the medium of a switch circuit controller, I do not wish to be limited to this particular form of controller. On the contrary, my invention may be practiced by substituting for the circuit controller D any suitable device which will control the local circuit as pointed out in the accompanying specification.

Although I have herein shown and described only three forms and arrangements of railway traffic controlling apparatus embodying my invention, it is understood that various changes and modifications may be

made therein within the scope of the appended claims without departing from the spirit and scope of my invention.

Having thus described my invention, what I claim is:

1. In a railway traffic controlling system for use with train-carried governing means arranged to display a less restrictive indication when the track occupied by the train is supplied with train governing current and a more restrictive indication when the supply of such current is interrupted, the combination of a stretch of railway track, a switch in said stretch, and means for supplying said stretch with train governing current throughout the length of the stretch when the switch is normal but for supplying train governing current to said stretch only between the forward end of the stretch and said switch when the switch is reversed.

2. In a railway traffic controlling system for use with train-carried governing means arranged to display a less restrictive indication when the track occupied by the train is supplied with train governing current and a more restrictive indication when the supply of such current is interrupted, the combination of a stretch of railway track, a switch in said stretch, and means for supplying said stretch with train governing current throughout the entire length of the stretch when the switch is normal but for supplying train governing current to said stretch between the switch and the forward end of the stretch and discontinuing such supply between the switch and the rear end of the stretch when the switch is reversed.

3. In a railway traffic controlling system for use with train-carried governing means arranged to display a less restrictive indication when the track occupied by the train is supplied with train governing current and a more restrictive indication when the supply of such current is interrupted, the combination of a stretch of track divided into a forward portion and a rear portion by a switch, means effective when said switch is normal for supplying train governing current to both said portions, but for supplying train governing current only to said forward portion when the switch is reversed.

4. In a railway traffic controlling system for use with train-carried governing means arranged to display a less restrictive indication when the track occupied by the train is supplied with train governing current and a more restrictive indication when the supply of such current is interrupted, the combination of a stretch of track divided into a forward portion and a rear portion by a switch, a source of train governing current for said stretch, and means for controlling the supply of train governing current from

said source to said rear portion but not to said forward portion in accordance with the position of said switch.

5. In a railway traffic controlling system for use with train-carried governing means arranged to display a less restrictive indication when the track occupied by the train is supplied with train governing current and a more restrictive indication when the supply of such current is interrupted, the combination of a stretch of track divided into a forward portion and a rear portion by a switch, a circuit controller operated by said switch, and means controlled by said circuit controller for supplying both said portions with train governing current when the switch is in one position but for supplying one only of said portions with train governing current when the switch is in a different position.

6. Railway traffic controlling apparatus comprising a stretch of track divided into a forward portion and a rear portion by a switch, a circuit controller operated by said switch, and means controlled by said circuit controller for supplying current to the rails of said stretch in parallel throughout their length when said switch is normal, but for supplying current to the rails of said forward portion only when said switch is reversed.

7. Railway traffic controlling apparatus comprising a stretch of track divided into a forward and a rear portion by a switch, a source of local current, a circuit controller operated by said switch and comprising two normally open contacts and a normally closed contact; a local circuit including said source, said normally closed contact and the rails of said stretch in parallel; and a second local circuit arranged to be closed only when said switch is reversed and including said source, said normally open contacts and the rails of said forward portion of track in parallel.

8. In a railway traffic controlling system for use with train carried governing means arranged to display a proceed indication when the track occupied by the train is supplied with train governing current and a stop indication when such supply is interrupted, the combination of a stretch of track provided with a switch, and means for causing a train in advance of said switch to receive a proceed indication but for causing a train in rear of such switch to receive a stop indication when such switch is reversed.

9. In a railway traffic controlling system for use with train carried governing means arranged to display a proceed indication when the track occupied by the train is supplied with train governing current and a stop indication when such supply is interrupted, the combination of a stretch of track

provided with a switch, and means for causing a train receding from said switch to receive a proceed indication, but for causing a train approaching said switch to receive a stop indication when the switch is reversed.

10. Railway traffic controlling apparatus comprising a stretch of railway track, a switch in said stretch, means for supplying train governing current to the rails occupied by a train receding from said switch in either direction regardless of the condition of the switch, but for interrupting such supply when the train is approaching the switch and the switch is reversed.

11. Railway traffic controlling apparatus comprising a stretch of track over which traffic moves in both directions, a switch in said stretch, means effective when a train moving in either direction occupies the stretch for supplying the entire section with train governing current when the switch is normal and for supplying only that portion of the stretch in advance of the switch with train governing current when the switch is reversed.

12. In a railway traffic controlling system for use with train-carried governing means arranged to display a less restrictive indication when the track occupied by the train is supplied with train governing current and a more restrictive indication when the supply of such current is interrupted, the combination of a stretch of track over which traffic moves in both directions, a switch in said stretch, and means for supplying said stretch with train governing current throughout its length or for a portion only of the stretch in accordance with the position of said switch.

13. Railway traffic controlling apparatus comprising a stretch of track over which traffic moves in both directions, a switch in said stretch, two sources of energy, means for supplying local current to said stretch from one said source or the other depending upon the direction of motion of a train occupying the stretch, and means for supplying such local current to the entire stretch or to a portion only of such stretch in advance of the switch in accordance with the position of the switch.

14. In a railway traffic controlling system for use with train-carried governing means arranged to display a less restrictive indication when the track occupied by the train is supplied with train governing current and a more restrictive indication when the supply of such current is interrupted, the combination of a stretch of track, a switch in said stretch, and means for supplying said stretch with train governing current throughout the length of the stretch when the switch is normal but for supplying train governing current to a portion only of said stretch when the switch is reversed.

15. Railway traffic controlling apparatus comprising a stretch of railway track, a switch in said stretch, and means controlled by traffic conditions for supplying said stretch with train governing current throughout the length of the stretch when the switch is normal but for supplying train governing current to said stretch only between the forward end of the stretch and said switch when the switch is reversed. 65
16. Railway traffic controlling apparatus comprising a stretch of railway track, a switch in said stretch, means responsive to traffic conditions for supplying train governing current to the rails occupied by a train receding from said switch in either direction regardless of the condition of the switch but for interrupting such supply when the train is approaching the switch and the switch is reversed. 70
17. In combination, a section of railway track containing a switch, and means associated with said section and controlled by said switch for governing a train in said section approaching said switch but not a train receding from said switch. 75
18. In combination, a section of railway track containing a switch, and means association with said section and operating when said switch is reversed to give a restrictive indication on a train approaching the switch but not on a train receding from the switch. 80
19. In combination, a section of railway track containing a switch, and means operating when said switch is reversed to give a more restrictive indication on a train in said section approaching the switch and a less restrictive indication on a train in said section receding from the switch. 85
20. In combination, a section of railway track containing a switch, means associated with said section for positively giving a less restrictive indication to a train throughout the section when traffic conditions in advance of the section are clear, and apparatus controlled by said switch and operating when the switch is reversed to prevent said means from giving said less restrictive indication to a train approaching the switch but not to a train receding from the switch. 90
21. In combination, a section of railway track containing a switch, a source of traffic controlling current for said section, and means operating when said switch is in the reverse position for disconnecting said source from a portion of the section and introducing an impedance between said source and the remainder of the section. 95
22. In combination, a section of railway track containing a switch, means for normally supplying traffic controlling current 100
- to the rails of said section in parallel throughout the length of the section, and means operating when said switch is in the reverse position for discontinuing the supply of said current to a portion of said circuit and introducing an impedance between the source of such current and the rails of the remainder of the section. 105
23. In combination, a section of railway track, a switch in said section, and means for applying to the rails of said section a relatively high traffic controlling voltage when said switch is in the normal position and a relatively low traffic controlling voltage when the switch is in the reverse position. 110
24. In combination, a section of railway track, a switch in said section, and means controlled by said switch for applying a relatively high traffic controlling voltage to the rails of said entire section or a relatively low traffic controlling voltage to the rails of only a portion of said section according to the position of said switch. 115
25. In combination, a section of railway track, a switch in said section, and means controlled by traffic conditions in advance of said section for applying to the rails of said section a relatively high traffic controlling voltage when said switch is in the normal position and a relatively low traffic controlling voltage when the switch is in the reverse position. 120
26. In combination, a section of railway track, a switch in said section, two impedances connected across the rails adjacent the entrance and exit ends respectively of said section, a source of current having its two terminals normally connected with said two impedances respectively, and means operating when said switch is reversed to disconnect one terminal of said source from the impedance at the entrance end of the section and to connect said one terminal with the track rails adjacent the switch. 125
27. In combination, a section of railway track, a switch in said section, two impedances connected across the rails adjacent the entrance and exit ends respectively of said section, a source of current having its two terminals normally connected with said two impedances respectively, and means operating when said switch is reversed to disconnect one terminal of said source from the impedance at the entrance end of the section and to connect said one terminal with the track rails adjacent the switch through a third impedance. 130

In testimony whereof I affix my signature.

HERBERT A. WALLACE.
